UNITED STATES PATENT OFFICE.

MARY BEALL WEATHERS, OF LENOIR, NORTH CAROLINA.

DESIGN FOR A CRADLE-GUARD.

SPECIFICATION forming part of Design No. 29,638, dated November 8, 1898.

Application filed October 13, 1898. Serial No. 693,453. Term of patent 3½ years.

To all whom it may concern:

Be it known that I, MARY BEALL WEATHERS, a citizen of the United States, residing at Lenoir, in the county of Caldwell and State 5 of North Carolina, have invented and produced a new and original Design for a Cradle-Guard, of which the following is a specification.

This invention relates to a new and original design for a cradle-guard; and it has for its object to provide a design of this character that shall be both useful and ornamental.

The leading feature of the design resides in an oblong approximately rectangular wire-fabric body having straight vertical side and end walls and an angular arched top portion.

The minor features of the design are the wire-fabric body having approximately diamond-shaped meshes and provided with an 20 arched top portion of an inverted-V shape and at its top corners with offstanding circular scroll projections.

In the drawings, Figure 1 is a perspective view of a cradle-guard embodying the herein-

described design. Fig. 2 is a vertical cross- 25 sectional view thereof.

The numeral 1 designates the body of the cradle-guard, which is of an oblong approximately rectangular outline, and said body is of wire fabric, preferably having diamond- 30 shaped meshes 2, and provided with straight vertical side and end walls 3 and 4, respectively, and an arched top portion 5 of an inverted-V shape in cross-section.

To complete the design, the wire-fabric 35 body is provided at its top corners with vertically-disposed offstanding circular scroll projections 6.

What is claimed is—

The design for a cradle-guard, herein shown 40 and described.

In testimony that I claim the foregoing as my own I have hereto affixed my signature in the presence of two witnesses.

MARY BEALL WEATHERS.
